GLOVE

Carroll G. Wells, Washington, D. C.

Application March 14, 1942, Serial No. 434,761

2 Claims. (Cl. 2—158)

(Granted under the act of March 3, 1883, as amended April 30, 1928; 370 O. G. 757)

The invention described herein, if patented, may be manufactured and used by or for the Government for governmental purposes, without the payment to me of any royalty thereon.

This invention relates to improvements in gloves adapted to be used by soldiers or hunters and others who require the full use of the fore or index finger for triggering a rifle as well as for other types of work for which this glove can be adapted.

Therefore, an important object of the invention is to provide a glove or mitten having an index finger covering superimposed upon the palm adjacent the crotch formed by the thumb covering so that the wearer can, when he so desires, insert his forefinger therein and thereby have full control and use thereof.

Another object of the invention is to attach or secure the forefinger covering to the palm in such a manner that the lower end of the forefinger covering will be secured to the upper edge of the glove and the upper end of the forefinger covering will lie in the crotch formed by the palm and thumb covering, that is, the finger covering will be in an inverted position, thereby permitting the forefinger covering to lie flat against the palm and be held in place by the thumb covering when not in use.

In all previously known gloves or mittens that have been used by soldiers and hunters and the like, an opening has been provided in the palm to promote the efficiency of the wearer in triggering his weapon but many difficulties have arisen in these types of hand coverings due to the fact that it has been difficult to devise means for fully closing the opening in order to protect the wearer's hands in severe weather.

Since it is an important feature of any glove or mitten of this type to keep the wearer's hands protected as well as to permit unobstructed use of the forefinger where the handling of weapons is concerned, it is thought that the present invention far surpasses any previously-known gloves that have been used for the above purpose.

While it has not been shown, an inner glove may be used or a lining may be incorporated in the glove to add extra protection to the wearer's hand in extremely cold climates and in this manner the utility of the glove is preserved; at the same time the wearer is insured of sufficient protection against the weather.

With the above and other objects and advantages in view the invention consists of features of construction, arrangement and operation of

parts which will appear in the specification and be finally pointed out in the claims.

While the preferred embodiment of the invention is shown it will be understood that slight changes in form and minor details of construction may be effected without departing from the spirit of the invention, to be hereinafter more fully described and illustrated in the accompanying drawing, wherein similar characters and references in the several figures indicate identical parts:

Fig. 1 represents the improved glove in elevation looking on the palm side showing the forefinger covering in the raised or used position.

Fig. 2 represents the improved glove in elevation looking on the palm side showing the finger in the lowered position or as it will be positioned when not in use, the thumb being bent back for better illustration.

Fig. 3 is a side elevation of the glove, partly broken away.

Fig. 4 is a diagrammatical sectional view of the glove, showing the forefinger inserted within the interior of the glove proper.

Fig. 5 is a transverse sectional view taken on line 5—5 of Fig. 2.

Referring to the drawing by numeral, 10 indicates the improved glove, which can be formed of any water-repellant material or the like, the palm being reinforced by means of a layer 11 of leather or the like to resist hard service and to promote longer wear. This layer 11 also extends and covers the inner surface of the thumb 12.

The real feature of the invention is the inverted finger covering 13 which will permit the wearer to trigger his weapon and permit free use of the forefinger for others engaged in work that requires the free use of the index finger. This is accomplished by securing the lower or open end of the covering 13 to the upper or outer edge of the glove while the upper or outer end of the finger will end in the crotch 14 formed by the palm and thumb of the glove 10. The finger covering 13 thus constructed will normally lie flat against the palm and be held in place at the crotch 14 of the glove by the thumb 12. The finger covering 13 is also short enough so that it will not interfere with the thumb when not in use. The reinforcing layer is also adapted to extend over the inner surface of the finger covering 13 so that it, as well as the palm of the glove, will stand excessive wear.

Another important improvement in this type of glove is that the covering 13 may be pushed

into the interior of the glove as shown in Fig. 4 and thus be positioned entirely out of the way of the wearer when it is not in use.

It will be seen from the foregoing that a very simple and inexpensive glove has been provided which possesses unusual advantages in the field for which it has been developed. It is thought, therefore, that the foregoing description, taken in connection with the accompanying drawing, will clearly illustrate the details of construction and mode of operation of the invention without any further extended description.

Having thus described the invention, what is claimed as new and desired to secure by Letters Patent is:

1. A glove, comprising a back portion, a palm and thumb portion joined thereto, a reinforcing layer secured to said palm portion and said thumb portion and an inverted superimposed

finger covering having the lower or open end thereof secured to the upper or outer edge of said palm portion, said finger covering being of such a length that the upper or closed end will fall short of the crotch formed by the palm portion and said thumb portion, said finger covering thereby being adapted to lie in a flattened position and having the outer or closed end retained in said palm portion by said thumb portion.

5 10 15 2. A glove, comprising a back portion, a palm portion joined thereto, an inverted superimposed finger covering the lower or open end of said covering joined to said palm portion, the usual thumb portion joined to said palm portion, and a reinforcing layer adapted to cover the palm portion and the inner faces of the superimposed finger covering and thumb portion.
